2,007,756

DEVICE FOR OPERATING CAR COUPLERS

Garth G. Gilpin, Riverside, Ill., assignor to Union Metal Products Company, Chicago, Ill., a corporation of Delaware

Original application April 3, 1929, Serial No. 352,126. Patent No. 1,798,464, dated March 31, 1931. Divided and this application March 14, 1931, Serial No. 522,582

3 Claims. (Cl. 213—167)

This invention relates to devices for operating railway car couplers having a pivoted knuckle provided with a tail engageable with a knuckle lock to which such device is operatively connected. The invention relates specifically to a railway car coupler having an anti-creep feature which is so formed that the lock can be raised to an unlocked position by the operating device, but can not be raised by the creeping action of the lock due to the service movements of the car. Some of such couplers are provided with a member mounted upon the underside of the coupler head for transmitting operating movements to the lock.

An object of the invention is to provide an operating rod for such couplers having a shank which is so formed and associated with parts of the car, or preferably a bracket mounted on the car, so as to stabilize the rod by gravity against a rotative movement thereof which would release the coupler anti-creep feature.

Another object of the invention is to provide such an operating rod with a depending handle and to associate the above mentioned bracket or car part with the handle to prevent a swinging movement of the handle which would cause a rotative movement of the operating rod and release the coupler anti-creep feature.

Another object of the invention is to provide the operating rod with an eccentric element co-operating with the above mentioned bracket or car part in such a way that the rotative movement of the rod (or a swinging movement of the handle) would elevate or raise one end (at least) of the rod so that the gravitational force of the rod tends to stabilize the rod against the rotative movement which would release the coupler anti-creep feature.

This objectionable swinging movement of the handle is caused by the irregular movements of the train in service, particularly the quick variations in the speed of the train.

In the drawing:

Figs. 1 and 2 show a typical application of my device to a railway car coupler.

Figs. 3 to 5 inclusive are enlargements showing the relation between the rod and the bracket.

The car coupler 2 is resiliently mounted on the car and arranged to move longitudinally and laterally of the car to accommodate the service movements thereof. For description of the operation and component parts of an ordinary coupler, reference is made to Patent No. 1,639,300 of August 16, 1927, which coupler is not only typical as showing the relation of the knuckle and the

lock, but also shows the member 3 rotatably mounted on the coupler for transmitting the operating movements to the lock which comprises a substantially horizontally disposed eye 4 for reception of a hook 5 on the operating rod 6 whereby rotation of the rod rotates the rotor member and operates the coupler.

The coupler shown in Patent No. 1,639,300 of August 16, 1927, also illustrates a typical coupler anti-creep feature wherein the lower part of the knuckle lock is provided with an obliquely positioned slot which is engaged by the operating mechanism. The coupler head is provided with a projection which is so positioned that a part of the operating mechanism engages it and prevents the lock from creeping upwardly. When the operating rod is rotated the same part of the operating mechanism moves upwardly until it engages the upper part of the obliquely positioned slot, in which position it is free to pass the projection on the coupler head and raise the coupler lock.

In the form of my invention illustrated the operating device comprises a rod 2 rotatably attached to the rotor member 3 on the coupler 4, which rod extends to adjacent the side wall 6 of the car where a handle 7 is provided for easy operation, eliminating the necessity of trainmen going between the cars.

A bracket 10 is mounted upon the car which is provided with a substantially vertical wall 11 and upwardly inclined surface 13 extending therefrom with a guard 15 above such surface. The operating rod 2 is provided with a depending handle 7 and an upwardly extending eccentric portion 17. The rod is normally supported by the bracket 10 adjacent the lower part 18 of the inclined surface 13 and preferably below the guard 15 with the upwardly extending eccentric portion 17 positioned adjacent the vertical wall 11 of the bracket. Even if the eccentric portion 17 is not used the inclined surface 13 maintains the handle 7 adjacent the wall 11 so that the rod is stabilized against a rotative movement. A retaining device 19 is preferably provided between the member forming the upwardly inclined surface and the guard member.

The rotor member 3 on the coupler is rotated by swinging the handle 7 of the rod outwardly from the car, which outwardly swinging movement engages the upwardly extending eccentric portion 17 of the rod with the wall 11 of the bracket and causes the rod to ride up the inclined surface 13, thereby physically raising the outer part of the rod. When the handle is re-

leased the weight of such outer part of the rod and the handle causes the rod to slide down the inclined surface and the handle to return to normal position. By this mechanism the rod is stabilized against a rotative movement.

The accompanying drawing illustrates the preferred form of the invention, though it is to be understood that the invention is not limited to the exact details of construction shown and described, as it is obvious that various modifications thereof, within the scope of the claims will occur to persons skilled in the art.

This is a division of my co-pending application Serial No. 352,126, filed April 3, 1929, Patent No. 1,798,464, March 31, 1931.

I claim:

1. In a railway car, an operating means for use with a coupler having a member mounted upon the coupler to move therewith and arranged to operate said coupler upon rotation thereof, said means comprising a bracket mounted upon the car having a substantially vertical wall with an upwardly inclined surface extending therefrom, and an operating rod operatively connected to the member which comprises a depending handle and an upwardly extending eccentric portion, said rod normally supported by said bracket adjacent the lower part of said inclined surface with the eccentric portion positioned adjacent said wall, whereby an outwardly swinging movement of the handle engages said eccentric portion with the wall of the bracket and causes the rod to ride up the inclined surface so that upon release of the handle the handle and operating rod return to normal position by gravity.
2. In a railway car, an operating means for use with a coupler having a member mounted upon the coupler to move therewith and arranged to operate said coupler upon rotation thereof, said means comprising a bracket mounted upon the

car having a substantially vertical wall with an upwardly inclined surface extending therefrom with a guard above said surface, and an operating rod operatively connected to the member which comprises a depending handle and an upwardly extending eccentric portion, said rod normally supported by said bracket adjacent the lower part of said inclined surface below said guard member with the eccentric portion positioned adjacent said wall, whereby an outwardly swinging movement of the handle engages said eccentric portion with the wall of the bracket and causes the rod to ride up the inclined surface so that upon release of the handle the handle and operating rod return to normal position by gravity.

3. In a railway car, an operating means for use with a coupler having a member mounted upon the coupler to move therewith and arranged to operate said coupler upon rotation thereof, said means comprising a bracket mounted upon the car having a substantially vertical wall with an upwardly inclined surface extending therefrom, said wall comprising an upper part above its junction with said inclined surface and a lower part below said junction, and an operating rod operatively connected to the member which comprises a depending handle and an upwardly extending eccentric portion, said rod normally supported by said bracket adjacent the lower part of said inclined surface with the eccentric portion positioned adjacent said upper part and the handle adjacent said lower part, whereby an outwardly swinging movement of the handle engages said eccentric portion with the upper part and causes the rod to ride up the inclined surface so that upon release of the handle the handle and operating rod return to normal position by gravity in engagement with said lower part, whereby the handle is stabilized against a swinging movement.
